TRUSS TYPE BRAKE BEAM CASTING

Walter H. Baselt, Flossmoor, Ill., assignor to
American Steel Foundries, Chicago, Ill., a cor-
poration of New Jersey

Application July 13, 1946, Serial No. 683,453

4 Claims. (Cl. 188—226.1)

1

This invention relates to railway brake beams and more particularly to a novel truss beam wherein the brake head and truss structure are integrally formed as a single casting.

A general object of the invention is to design a novel brake beam casting of light and economical construction and capable of withstanding the stresses to which such a beam is subjected under railway service conditions.

Another object of the invention is to design a novel brake beam such as above described wherein each end of the beam is provided with a guide lug adapted for reception within an associated support structure such as a bracket on the side frame of a railway freight car truck.

The foregoing and other objects and advantages of the invention will become apparent from a consideration of the following specification and the accompanying drawings wherein:

Figure 1 is a fragmentary top plan view of a brake beam embodying the invention, only one end thereof being illustrated inasmuch as the brake beam is symmetrical about its transverse center line;

Figure 2 is a front view of the beam shown in Figure 1;

Figure 3 is an end view of the beam shown in Figures 1 and 2 and illustrating the brake beam strut; and

Figure 4 is a sectional view taken in the vertical plane indicated by the line 4—4 of Figure 1.

Describing the invention in detail, the novel brake beam is formed as a single casting comprising a T-section compression member 2 with a front substantially vertical web 4 forming the head of the T, and a rear substantially horizontal web 6 forming the leg of the T. A tension member 8 merges with both webs 4 and 6, the web 4 being extended arcuately forward as at 7 to define a gusset 9 formed as a continuation of the web 6 at its juncture with the tension member 8.

The tension member 8 merges with a rear vertical wall 10 of a brake head generally designated 12, said head being of conventional form with a front wall 14 having a conventional keyway 16 (Figures 1 and 2) for the reception of associated key means (not shown) adapted to secure a brake shoe (not shown) to the front surface of the wall 14.

Inboard and outboard gussets 18 and 20 (Figure 1) are connected between the tension member 8 and the brake head walls 10 and 14 to strengthen the connection of the head 12 to the truss structure defined by the tension and compression members 2 and 8, said truss structure

2

comprising a conventional strut 21 (Figure 3) connected between the tension and compression members and integrally formed therewith, said strut being of more or less conventional form and being adapted for pivotal securement in conventional manner to an associated brake lever (not shown).

It is noted that the tension member 8 is tapered in thickness as at 23 outboardly of the vertical brake head wall 10 to afford a relatively light structure which, as above noted, is reinforced by the outboard gusset 20. It may also be noted that the gussets 18 and 20 are preferably of approximately the same thickness and lie in the same planes as the web 6 of the compression member 2, thereby forming a continuation of said web 6.

A guide lug 22 is formed on the outboard end on the beam for cooperation with an associated support structure (not shown) to support and guide the beam in its diagonal movement to and from an associated rotating wheel and axle assembly (not shown). The lug 22 is preferably disposed in the plane of said movement and is diagonal to the plane of the truss structure, as best seen in Figure 3. The lug merges with the tapered outboard extremity of the tension member 8 and with the front wall 14 of the brake head, as well as the outboard gusset 20 connecting said front wall with the tapered portion 23 of the tension member 8.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. A brake beam comprising a single casting including a T-section compression member having a front substantially vertical web forming the head of the T and a rear substantially horizontal web forming the leg of the T, the outboard extremity of said front web extending arcuately forward of the intermediate portion of the front web, a diagonal tension member merging with the forward extremity of said front web and extending outboardly thereof to merge with the rear web, a brake head having a rear wall merging with the tension member, a front wall angularly related to the rear wall, a guide lug merging with the outboard margins of the tension member and the front wall, and gussets connecting the front wall to the tension member in-

boardly and outboardly of the rear wall, the outboard gusset merging with the lug.

2. A brake beam, according to claim 1, wherein the guide lug is diagonal to the plane of the tension member and the outboard end of the tension member merges with the rear end of the lug and slopes upwardly from the lug to the rear brake head wall.

3. A brake beam comprising a single casting including a T-section compression member having a front substantially vertical web forming the head of the T and a rear substantially horizontal web forming the leg of the T, the outboard extremity of said front web extending forwardly from the intermediate portion thereof, a diagonal tension member merging with the forward extremity of the front web and extending outboardly thereof to merge with the rear web, a brake head having a rear wall merging with the tension member and having a front wall angu- 15

larly related to the rear wall, and gussets connecting the front wall to the tension member inboardly and outboardly of the rear wall.

4. A brake beam, according to claim 3, wherein the gussets are substantially coplanar with the rear web of the compression member and approximately bisect the forward surface of the tension member.
